CLAIM

The ornamental design for a pad painter as shown and described.

DESCRIPTION

FIG. 1 is a top perspective view of a pad painter according to our new design;

FIG. 2 is a top view thereof;

FIG. 3 is an enlarged portion taken from line 3 in FIG. 2;

FIG. 4 is a bottom view thereof;

FIG. 5 is an enlarged portion taken from line 5 in FIG. 4;

FIG. 6 is a left side view thereof;

FIG. 7 is a right side view thereof;

FIG. 8 is a rear bottom view; and,

FIG. 9 is a rear view thereof.

The broken lines illustrate unclaimed portions of the pad painter and form no part of the claimed design. The dot-dash lines illustrate the boundaries of portions of the pad painter shown enlarged in other figures and form a part of the claimed design.
